UNITED STATES PATENT OFFICE.

PERRY C. SMITH, OF INDIANAPOLIS, INDIANA.

DESIGN FOR A CREAM-SEPARATOR-BOTTOM BLANK.

SPECIFICATION forming part of Design No. 34,374, dated April 16, 1901.

Application filed September 24, 1900. Serial No. 31,005. Term of patent 3½ years.

To all whom it may concern:

Be it known that I, PERRY C. SMITH, a citizen of the United States, residing at Indianapolis, in the county of Marion and State of Indiana, have invented and produced a certain new and original Design for a Cream-Separator-Bottom Blank, of which the following is a specification.

The drawing illustrates a top or plan view of 10 a blank for the bottom of a cream-separator.

As shown in the drawing, the leading or material feature of my design consists of a sheet of metal having an approximately circular body portion, on one side or edge of 15 which circular part is a projection, and adjacent to said projection is a circular opening which has a V-shaped notch forming a communication with the outside through said projection or enlargement.

20 A represents the approximately circular

body portion; B, the projection or enlargement; C, the circular opening, and D the serration or V-shaped notch which bisects the enlargement on the side of the body A and tapers toward and enters the opening C.

25

It is apparent that this design is applicable to vessels other than cream-separators.

Having described my invention, what I claim as new, and desire to secure by Letters Patent, is—

30

The design for a cream-separator-bottom blank, as herein shown and described.

In witness whereof I have hereunto set my hand and seal, at Indianapolis, Indiana, this 19th day of September, A. D. 1900.

PERRY C. SMITH. [L. S.]
